FOLDED BOX

Paul Flach, Chemnitz, Germany

Application March 28, 1935, Serial No. 13,543
In Germany March 29, 1934

21 Claims. (Cl. 229—34)

This invention relates to folded boxes, and more particularly to those in which the cover and bottom part are each made from a separate cut-out or blank in such a manner that the side walls of which two opposite ones are provided at the ends with extensions for folding in, can be connected together by means of tabs provided on the other opposite side walls or end walls. The invention relates to the particular method of locking the tabs with the side walls of the box member which do not belong thereto. This locking is effected by locking tongues provided on the tabs being introduced into corresponding cuts or recesses in the side walls. Apart from the security which this locking offers against the loosening of the box member on account of the particular method of making the recesses for the locking tongues, the further advantage is obtained of an extraordinary strengthening of the 20 corners of the box member and a high stability thereof.

In the drawings a number of constructional examples of the invention are illustrated by way of example in the form of blanks for making the 25 boxes according to the invention, laid out flat.

Fig. 1 shows a folding box blank according to the invention partly laid out flat. Fig. 2 shows a modified form in a similar manner. Fig. 2a shows this construction with the box partly 30 folded together. Fig. 3 shows a third modification, partly laid out flat, and Fig. 4 shows in a similar manner a fourth modification, only a part of the blank being shown. Fig. 4a shows in perspective the blank according to Fig. 4 partly 35 folded into a box.

In all constructional forms the blank has a middle or main part 1, which forms, for example, the bottom of the box member. Adjoining the middle or main part and connected thereto along 40 folding lines 2a, 2b and 3a, 3b respectively are the end parts or walls 2, 2 and the side parts or walls 3, 3, which later will form the sides of the box member. At the long edges of the parts 3, 3 are attached side wall tabs 4, 4 of somewhat less 45 breadth, and at the narrow sides the terminal extensions 5, 5 are attached. At the narrow sides of the parts 4 there are hinged flaps 6, which are shown on the left-hand side of the drawings flat, but on the right-hand side folded over on to the 50 parts 4.

Symmetrically to the lines 6a and 6b connecting the flaps 6 with the part 4, in the constructional form according to Fig. 1, semicircular recesses 7 open on the outside are provided in the 55 parts 4 and 6. When the flaps 6 are folded over

on to the part 4 in the manner shown on the right-hand side of the drawing, these recesses take on the shape of a quarter of a circle, and in the box when folded together serve for receiving the locking tongues 8 which are provided on the narrow sides of the end wall tabs 9, 9 attached to the parts 2, 2 by folding lines 9a or 9b in such a manner that their free straight edges lie in the extension of the folding lines 10a, 10b connecting the tabs 9 with the adjoining strips 10. The form of the tongues 8 corresponds to that of the recesses 7.

The blank is folded together in the following manner. First the flaps 6 are folded down on to the parts 4, as shown in the right-hand part of the drawing, and stuck down. Then the parts 4 are folded down on to the side walls 3 and stuck thereto (Fig. 2a). The side walls 3 are then raised, and care is taken that their extensions 5 turn inwards, which requires these extensions to 20 be turned at right-angles. Then the end walls 2, 2 are raised and their tabs 9 are folded inwards over the extensions 5, 5 so that the strips 10, 10 come to lie on the middle part 1 and are folded at right-angles. As soon as the lines 10a 25 and 10b have reached the lines 2a, 2b the locking tongues 8 come opposite to the recesses 7 and spring into these recesses on account of the elasticity of the card material, whereby locking 30 is effected. Automatic releasing of the locking is impossible owing to the resilience of the material which holds the tongues 8 in the recesses 7.

At the four corners of the box member there are three layers of card superposed. This gives a considerable reinforcement for the corners, which 35 are especially sensitive to being pushed in and other stresses; moreover, on account of the doubled layer of material adjoining the recess 7, the locking tongues 8 are caused to hold securely 40 in the recesses 7. The connection of the flaps 6 with the parts 4, and of these parts with the parts 3, can of course, be effected otherwise than by 45 means of an adhesive, for example by stapling or stitching. In the same manner as described both the bottom part and cover part can be made 50 for boxes with lids. The new arrangement, however, can naturally be used for folded boxes of other kinds. All this applies also to the forms 55 shown in Figs. 2-4.

For further increasing the security of the locking, in the form illustrated in Fig. 2, the recesses for receiving the locking tongues are cut away underneath, in such a manner that the recess in the flap which comes to lie on the inside when the box is folded together, overlaps the edge of 60

the recess of the tongue, which produces a doubled depth of the rest, forming a kind of fold so that the locking tongues can enter behind the overlapping edges in the locking position.

- 5 As shown in Fig. 2 the construction of the blank is fundamentally the same as in the previously described construction; it differs essentially only in that the recesses 7 do not lie exactly symmetrical with respect to the lines 6b 10 as the part 1a in the flap 6 is somewhat greater than the part 1b in the tab 4, so that when the flap 6 is folded over the part 4, as shown on the right-hand side on the drawing, the edges of the recesses 1a, as shown on the left-hand side 15 above by the broken line, are set back behind the edges of the recesses 1b, and when the part 4 is folded inwardly over the part 3, the edges of the recesses 1b, with the edges of the recesses 1a, will form under-cut folds in which 20 the locking tongues 8 can slide when the box is folded together. The locking tongues can then not readily come out of their places, as they are held by the projecting edges of the recesses 1b. The size of the locking tongues 8 corresponds 25 preferably with that of the recesses 1a.

In the constructional form according to Fig. 3 the construction of the blank as regards the parts 1-10 is substantially the same as in Fig. 2. There are, however, further or secondary flaps 11 30 hinged on to the primary flaps 6 at 11a, which are provided with recesses 12 in the form of a quarter circle. The recesses 12 and 1a lie symmetrically with respect to the folding lines 11a.

The blank is prepared as follows. First of all 35 the flaps 11 together with the flaps 6 are folded about the line 6b over on the parts 4. The flaps 11 are then folded in a reverse direction about the line 11a, leaving a part of flap 11 projecting parallel to terminal extensions 5 and 40 beyond the part 4. This procedure may of course be reversed by first folding part 11 backward on line 11a and then folding flaps 6 and 11 along the line 6b. The result in both cases is shown on the right-hand side of Fig. 3. In this 45 position the parts are gummed or otherwise fastened together. The blank is then ready for dispatch. The folding together to form the box is effected as in the previous cases by the side parts 3 first being raised with the superposed 50 extensions 5 and 11 turned inwards at right-angles after which the end walls 2 are raised and the tabs 9 are folded inwards so that the locking tongues 8 engage in the places formed by the recesses 1a, 1b and 12 and the strips 10 55 then lie on the bottom of the box.

By the construction of the blank according to Fig. 3 the security of the locking of the locking tongues is further increased because the edges of the place for the locking tongues consists of three layers of material; in addition, since the side walls of the box near to the corners have four layers of material a further reinforcement is obtained of the corners of the box, which are specially sensitive to mechanical strain.

65 The construction according to Fig. 4 in which, for the sake of simplicity, only a part of the blank is shown, differs from those described above essentially in that the recesses 12 in the flaps 11 lie symmetrically with the recesses 1b of the parts 4 with respect to the folding lines 11a between 70 the flaps 11 and 6 in such a manner that when the flaps 11 are folded over the flaps 6 and over the parts 4, the recesses 12 and 1b coincide. In this case also the recesses 1b are made somewhat smaller than the recesses 12, in order to

form under-cut edges. Furthermore, another folding line 12b is provided in the extension of the edge 12a of the recess 12, which, when the flap 11 is folded over about the line 11a, as illustrated on the right-hand side of Fig. 4, coincides with the line 6b between the flap 6 and the part 4. The inner parts of flap 11 will then coincide with flaps 6. These coinciding parts will thus extend beyond parts 4, and parallel to terminal extensions 5 as shown on the right-hand of Fig. 4. These coinciding parts may then be turned inwards together with extensions 5 when the side walls 3 are raised. The flaps 11 are again gummed or otherwise secured to the parts 4 which are also secured to the parts 3. 15 The folding of the box from the blank thus formed is effected in the manner described above. In this way there is obtained near to the corners of the box a three-fold thickness of material for the longitudinal walls, a five-fold 20 thickness for the narrow side or end walls and a corresponding reinforcement of the corners of the box. The edges of the places for the locking tongues 8 also have two layers of material.

As a particular advantage for all the constructions described it may be mentioned that the new construction of the locking parts, on account of the great security of the locking obtained thereby, makes possible a very rapid and convenient working in folding together the 30 blanks, which is of great importance as regards manufacturing costs, since it is mainly a question of hand work.

Where in the above description, as well as in the claims, a folding box is mentioned this must 35 be taken to include not only a complete folding box consisting of a lower part and a cover part, but also the lower part or the cover part alone. The construction is claimed also not only for the completely folded box or box members, but also 40 for the blank, whether completely spread out or in a set, in which, as shown in the right-hand side of the drawings, individual parts of the blank are secured by adhesive or stapling.

I claim:

1. A folding box blank comprising a main part, two opposite side walls, two opposite end walls, each of said end walls having an end wall tab, an extension on each end of each of said side walls, a side wall tab on each of said side walls 50 and a flap on each end of each of said side wall tabs, said flaps bent down on to their respective side wall tabs and attached thereto.

2. A folding box blank comprising a main part, two opposite side walls, two opposite end walls, 55 each of said end walls having an end wall tab, an extension on each end of each of said side walls, a side wall tab on each of said side walls, a flap on each end of each of said side wall tabs, a recess at each end of each of said side wall tabs, 60 a recess in each of said flaps adapted when the flaps are folded down to coincide substantially with the side wall tab recess, and a locking tongue on each end of each of said end wall tabs adapted when the box is folded together to engage one of said side wall tab recesses.

3. A folding box blank comprising a main part, two opposite side walls, two opposite end walls, each of said end walls having an end wall tab, an extension on each end of each of said side 70 walls, a side wall tab on each of said side walls, a flap on each end of each of said side wall tabs, a recess at each end of each of said side wall tabs, a recess in each of said flaps adjacent to one of the side wall tab recesses and adapted sub- 75

stantially to coincide with the side wall tab recess when the flap is folded down and a locking tongue on each end of each of said end wall tabs adapted when the box is folded together to engage one of said side wall tab recesses.

4. A folding box blank comprising a main part, two opposite side walls, two opposite end walls, each of said end walls having an end wall tab, an extension on each end of each of said side walls, 10 a side wall tab on each of said side walls, a flap on each end of each of said side wall tabs, a recess at each end of each of said side wall tabs, a recess in each of said flaps adapted substantially to coincide with the side wall tab recess 15 when the flaps are folded down, said flap recesses being of larger size than their respective side wall tab recesses, and a locking tongue on each end of each of said end wall tabs adapted when the box is folded together to engage one of said side 20 wall tab recesses.

28 wall tab recesses.

5. A folding box blank comprising a main part, two opposite side walls, two opposite end walls, each of said end walls having an end wall tab, an extension on each end of each of said side walls, a side wall tab on each of said side walls, a flap on each end of each of said side wall tabs, a recess at each end of said side wall tabs, a recess in each of said flaps being of larger size than its respective side wall tab recess and adapted substantially to coincide with the side wall tab recess when the flaps are folded down, and a locking tongue on each end of each of said end wall tabs adapted when the box is folded together to engage one of said side wall tab recesses.

6. A folding box blank comprising a main part, two opposite side walls, two opposite end walls, each of said end walls having an end wall tab, an extension on each end of each of said side walls, a side wall tab on each of said side walls, a flap on each end of each of said side wall tabs, a recess at each end of each of said side wall tabs, a recess in each of said flaps of larger size than the respective side wall tab recess and adapted substantially to coincide with the side wall tab recess when the respective flaps are folded down, and a locking tongue on each end of each of said end wall tabs adapted when the box is folded together to engage one of said side wall recesses, each of said flaps being folded down on to its respective side wall tab and secured thereto.

7. A folding box blank comprising a main part, two opposite side walls, two opposite end walls, each of said end walls having an end wall tab, an extension on each end of each of said side walls, a side wall tab on each of said side walls, a flap on each end of each of said side wall tabs, a recess at each end of each of said side wall tabs, 60 a recess in each of said flaps, being of larger size than its respective side wall tab recess and adapted substantially to coincide with the respective side wall tab recess when the respective flaps are folded down, and a locking tongue on each end 65 of each of said end wall tabs adapted when the box is folded together to engage one of said side wall tab recesses, each of said flaps being folded down on to its respective side wall tab and secured thereto, and each of said side wall tabs 70 being folded down on to its respective side wall and secured thereto.

8. A folding box blank comprising a main part, two opposite side walls, two opposite end walls, each of said end walls having an end wall tab, 7.5 an extension on each end of each of said side walls.

walls, a side wall tab on each of said side walls, a flap on each end of each of said side wall tabs, a recess at each end of each of said side wall tabs, a recess in each of said flaps, being of larger size than its respective side wall tab recess and adapted substantially to coincide with the respective side wall tab recess when the respective flaps are folded down, and a locking tongue on each end of each of said end wall tabs adapted when the box is folded together to engage one of said side wall tab recesses, each of said flaps being folded down on to its respective side wall tab and secured thereto by sticking, and each of said side wall tabs being folded down on to its respective side wall and secured thereto by sticking.

9. A folding box comprising a main part, two opposite side walls, two opposite end walls, each of said end walls having an end wall tab, an extension on each end of each of said side walls, a side wall tab on each of said side walls, a flap on each end of each of said side wall tabs, said flaps bent down on to their respective side wall tabs, and locking means to maintain said side walls and said end walls in an upwardly bent and assembled relation after the side wall tabs have been folded down to their respective side walls and the extensions have been turned inwards at right-angles. 20 25

10. A folded box comprising a main part, two
opposite side walls, two opposite end walls, each
of said end walls having an end wall tab, an
extension on each end of each of said side walls,
a side wall tab on each of said side walls, a
flap on each end of each of said side wall tabs,
a recess at each end of each of said side wall
tabs, a recess in each of said flaps adapted sub-
stantially to coincide with the respective side
wall tab recess when the respective flaps are
folded down, and a locking tongue on each end
of each of said end wall tabs, each of said locking
tongues adapted when the box is folded together
to engage one of said side wall tab recesses. 30
35
40

11. A folding box comprising a main part, two opposite side walls, two opposite end walls, 45 each of said end walls having an end wall tab, an extension on each end of each of said side walls, a side wall tab on each of said side walls, a flap on each end of each of said side wall tabs, a recess at each end of each of said side wall tabs, a recess in each of said flaps adapted substantially to coincide with the respective side wall tab recess when the respective flaps are folded down, and a locking tongue on each end of each of said end wall tabs, each of said locking tongues adapted when the box is folded together to engage one of said side wall tab recesses and one of said flap recesses. 50 55

12. A folding box comprising a main part, two opposite side walls, two opposite end walls, each of said end walls having an end wall tab, an extension on each end of each of said side walls, a side wall tab on each of said side walls, a flap on each end of each of said side wall tabs, a recess at each end of each of said side wall tabs, a recess in each of said flaps adapted substantially to coincide with the respective side wall tab recess when the respective flaps are folded down, said flap recesses being of larger size than said side wall tab recesses, and a locking tongue on each end of each of said end wall tabs, each of said locking tongues adapted when the box is folded together to engage one of said recesses. 60 65 70

13. A folding box comprising a main part, two opposite side walls, two opposite end walls, each

- of said end walls having an end wall tab, an extension on each end of each of said side walls, a side wall tab on each of said side walls, a flap on each end of each of said side wall tabs, a recess at each end of each of said side wall tabs, a recess in each of said flaps adapted substantially to coincide with the respective side wall tab recess when the respective flaps are folded down, said flap recesses being of larger size than 5 said wall tab recesses, and a locking tongue on each end of each of said end wall tabs adapted when the box is folded together to engage one of said side wall tab recesses, each of said flaps being folded down on to its respective side wall tab and secured thereto by sticking, and each of 10 said side wall tabs being folded down on to its respective side wall and secured thereto by sticking.
- 15 14. A folding box blank comprising a main part, two opposite side walls, two opposite end walls, each of said end walls having an end wall tab, an extension on each end of each of said side walls, a side wall tab on each of said side walls, a flap on each end of each of said side wall tabs, said flaps being bent down on to their respective side wall tabs, and a secondary flap hinged to each of said flaps.
- 20 15. A folding box comprising a main part, two opposite side walls, two opposite end walls, each of said end walls having an end wall tab, an extension on each end of each of said side walls, a side wall tab on each of said side walls, a flap on each end of each of said side wall tabs, a secondary flap hinged to each of said first-named flaps and being bent down on to it for reinforcement, and locking elements adapted to maintain said side walls and said end walls in an upwardly bent and assembled relation after the side wall tabs have been folded down on to the side walls 25 and secured thereto by sticking.
- 25 16. A folding box blank comprising a main part, two opposite side walls, two opposite end walls, each of said end walls having an end wall tab, an extension on each end of each of said side walls, a side wall tab on each of said side walls, a flap on each end of each of said side wall tabs, said flaps being bent down on to their respective side wall tabs, a secondary flap hinged to each of said flaps, a recess in each end of said side wall tabs, a further recess in each of said secondary flaps, said further recesses adapted to coincide with the corresponding recesses of said side wall tabs on said secondary flaps being folded down to said flaps, and a locking tongue 30 on each end of each of said end wall tabs.
- 30 17. A folding box blank comprising a main part, two opposite side walls, two opposite end walls, each of said end walls having an end wall tab, an extension on each end of each of said side walls, a side wall tab on each of said side walls, a flap on each end of each of said side wall tabs, a secondary flap hinged to each of said flaps in a score line, a recess on each end of each of said side wall tabs, a further recess in each of said secondary flaps, said recesses and said further recesses being disposed substantially symmetrically to the score lines connecting said flaps and said secondary flaps, and a locking tongue on each end of each of said end wall tabs adapted when the box is folded together to engage one of said recesses.
- 35 18. A folding box blank comprising a main part, two opposite side walls, two opposite end walls, each of said end walls having an end wall tab, an extension on each end of each of said side walls, a side wall tab on each of said side walls, a flap on each end of each of said side wall tabs, and a secondary flap hinged to each of said flaps, said secondary flaps being folded down on to said flaps about the score lines connecting them to their respective flaps, said flaps together with their secondary flaps being folded down on to their adjacent side wall tabs, and said side wall tabs being together with their respective flaps and secondary flaps folded down on to the adjacent side walls and stuck thereto.
